(57) CLAIM

The ornamental design for a fashionable chest placard, as shown and described.

DESCRIPTION

FIG. 1 is a perspective front view of a fashionable chest placard, showing my new design;

FIG. 2 is a top front perspective view thereof;

FIG. 3 is a front elevation view thereof;

FIG. 4 is a rear elevation view thereof;

FIG. 5 is a left side elevation view thereof; the right side elevation view being a mirror image thereof;

FIG. 6 is a top plan view thereof; and,

FIG. 7 is a bottom plan view thereof.

The broken lines showing a human silhouette in FIG. 1 represent environment subject matter only and form no part of the claimed design. The other broken lines in FIGS. 1 through 7 represent portions of the fashionable chest placard that form no part of the claimed design.
